US0D1106595S

(12) **United States Design Patent** (10) **Patent No.:** **US D1,106,595 S**
Zhao et al. (45) **Date of Patent:** **** Dec. 16, 2025**

(54) **EARMUFFS**

(71) Applicant: **SHENZHEN THOUSANDSHORES TECHNOLOGY CO., LTD.**,
 Guangdong (CN)

(72) Inventors: **Jinying Zhao**, Shenzhen (CN);
Shichang Liu, Shenzhen (CN)

(73) Assignee: **SHENZHEN THOUSANDSHORES TECHNOLOGY CO., LTD.**, Shenzhen (CN)

(**) Term: **15 Years**

(21) Appl. No.: **29/960,081**

(22) Filed: **Aug. 28, 2024**

(51) **LOC (15) Cl.** **29-02**

(52) **U.S. Cl.**

USPC **D29/112**

(57)

CLAIM

The ornamental design for earmuffs as shown and described.

DESCRIPTION

FIG. 1 is a perspective view of earmuffs showing our new design;
 FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines indicate portions of the earmuffs that form no part of the claimed design.

1 Claim, 7 Drawing Sheets
